(57) **CLAIM**

The ornamental design for an audio headband padset for protective helmet, as shown and described.

DESCRIPTION

FIG. 1 is a front, right, top perspective view of the audio headband padset for protective helmet showing my new design;

FIG. 2 is a front elevational view thereof;

FIG. 3 is a back elevational view thereof;

FIG. 4 is top plan view thereof;

FIG. 5 is a bottom plan view thereof; and,

FIG. 6 is a right side elevational view thereof, the left side elevational view being identical.

The dotted line presentation of the audio headband is for descriptive purposes only, and forms no part of the claimed design.
